CLAIM

The ornamental design for a manifold for pressure gauges, as shown.

DESCRIPTION

FIG. 1 is a perspective view of a manifold for pressure gauges showing our new design;

FIG. 2 is a front elevational view thereof;

FIG. 3 is a bottom plan view thereof;

FIG. 4 is a top plan view thereof;

FIG. 5 is a rear elevational view thereof;

FIG. 6 is a left side elevational view thereof; and

FIG. 7 is a right side elevational view thereof.

FIG. 8 is a perspective view of a manifold for pressure gauges showing our new design;

FIG. 9 is a front elevational view thereof, the rear elevational view being a mirror image thereof;

FIG. 10 is a bottom plan view thereof;

FIG. 11 is a left side elevational view thereof;

FIG. 12 is a right side elevational view thereof; and,

FIG. 13 is a top plan view thereof.
